(57) **CLAIM**

The ornamental design for a body camera, as shown and described.

DESCRIPTION

FIG. 1 is a left front isometric view of a body camera of our new design;

FIG. 2 is a right front isometric view of the body camera shown in FIG. 1;

FIG. 3 is a front view of the body camera shown in FIG. 1; FIG. 4 is a top view of the body camera shown in FIG. 1; FIG. 5 is a bottom view of the body camera shown in FIG. 1;

FIG. 6 is a left side view of the body camera shown in FIG. 1; and,

FIG. 7 is a right side view of the body camera shown in FIG. 1.

The broken lines in the drawing depict portions of the body camera that form no part of the claimed design.
